O. E. BUCKLEY

ARTIFICIAL LINE

Filed Aug. 3, 1922

UNITED STATES PATENT OFFICE.

OLIVER E. BUCKLEY, OF MAPLEWOOD, NEW JERSEY, ASSIGNOR TO WESTERN ELECTRIC COMPANY, INCORPORATED, OF NEW YORK, N. Y., A CORPORATION OF NEW YORK.

ARTIFICIAL LINE.

Application filed August 3, 1922. Serial No. 579,356.

To all whom it may concern:

Be it known that I, OLIVER E. BUCKLEY, a citizen of the United States of America, residing at Maplewood, in the county of Essex and State of New Jersey, have invented certain new and useful Improvements in Artificial Lines, of which the following is a full, clear, concise, and exact description.

10. The principal object of the invention is to provide an artificial line that shall accurately simulate a long signaling conductor. In this specification there is disclosed as an example of the invention, a balancing network for the duplex operation of a long high-speed continuously loaded ocean telegraph cable.

Fig. 1 is a diagram showing the particular artificial line here disclosed as representing the invention. Fig. 2 is a diagram showing the current in the conductor at various distances from the sending end. Fig. 3 is a permeability diagram for the loading material. Fig. 4 is a diagram showing the effect of variation of air gap on effective permeability and Fig. 5 is a diagram showing the effect on permeability of superposed constant magnetizing force.

In the United States patent application, Serial No. 492,725, filed August 16, 1921, (corresponding to British Patent No. 184,774) in the name of O. E. Buckley, there is disclosed a continuously loaded conductor suitable for use as a long ocean telegraph cable. In the specification of that case it is pointed out that the loading of long ocean telegraph cables has heretofore been found of no practical advantage. Indeed, no telegraph cable of length greater than 100 nauts has been loaded for any purpose, and the only loading of shorter cables has been primarily for telephone use and in some cases secondarily for superposed telegraphy.

45. A telephone cable of length 100 nauts has been loaded with a wrapping of small iron wire, but the cable conductor described in the Buckley patent application is loaded with tape of a special composition called "permalloy" which is fully described in the specification of that application.

50. A suitable form of permalloy is obtained by fusing together iron and nickel in the respective proportion of 21½ per cent and

78½ per cent and forming the composition 55 into a tape of suitable dimensions. This permalloy tape is applied helically to the conductor, with the edges abutting. Thereafter, the taped conductor is given a heat treatment described in the specification referred to, which leaves the permalloy tape 60 in a condition of very high permeability for low magnetizing forces, many times higher than for the best samples of iron heretofore in use.

65. The high permeability of the loading material gives the loaded conductor a high inductance, thus diminishing the attenuation, and facilitates the transmission of signals at much higher frequency than has been 70 possible on the unloaded cable conductors heretofore in use.

In the operation of long ocean cables it has been quite usual heretofore to operate them duplex. For this purpose, as is well 75 known, artificial lines are provided at both ends, each of which simulates the cable electrically to a practicable degree, and the actual cable and the artificial line are connected up as arms of a Wheatstone bridge. 80 The matter of making and adjusting an artificial line so that it will simulate a long ocean cable with sufficient accuracy has been one of considerable difficulty, even though the cable was not loaded. In the United 85 States patent application referred to, the continuously loaded line is disclosed as being operated only one way. In the particular example there considered, the one way operation was shown to be at about 90 ten times the speed for the unloaded cable with which comparison was proper. The unloaded cable has its message capacity increased somewhat less than 100 per cent by duplex operation, so that the message capacity of the continuously loaded cable operated simplex is more than five times the message capacity of the unloaded cable operated duplex.

100. The problem of balancing the continuously loaded cable has several elements of difficulty that may be noticed. The non-loaded cable has resistance and capacity, whereas its leakance and inductance are almost negligible. The loaded cable has a large amount of inductance which, of course, must be simulated in the artificial line, thus increasing the difficulty of effecting a bal-

ance. Moreover, the inductance varies with respect to the current, whereas the factors met in balancing the unloaded cable, namely, resistance and capacity, are substantially the same for different currents. Still further, the effective resistance of the line is determined, in a measure, by eddy current losses and other effects in the loading material, so that this effective resistance for the loaded cable varies with change of the current, whereas for the non-loaded cable the effective resistance is substantially constant.

With the conditions in view for simulating the long continuously loaded conductor, I have devised an artificial line that is like the cable conductor with respect to all the essential constants involved, and may be used to balance such a conductor for duplex operation, and may be adjusted in a convenient manner to secure the desired balance.

The particular loaded cable considered by way of example in the Buckley patent application has a cylindrical copper conductor of diameter 0.168 inch. This is enveloped by a helically wound tape of permalloy of thickness 0.006 inch and width 0.125 inch, which makes the overall diameter of the taped conductor 0.180 inch. When applied in this way, the permalloy tape shows a virtual permeability of 2,000 or more, whereas for any grade of iron heretofore available the figure would not be over 200. By virtue of this extraordinary property of permalloy, its high permeability at low magnetizing forces, the conductor loaded in this way serves for the high speed telegraph transmission described in the Buckley United States patent specification already identified.

After assembly of the copper conductor and its loading material, as described, they are put through a heat treatment which develops the high permeability referred to. Then the cover of gutta percha insulation, wires, etc., is applied. The cable described by way of example has a length of 2,000 nauts. The magnetic properties of the loading material will appear more fully in connection with the following description of the artificial line.

Referring to Fig. 1, the cable already described is indicated at 10. The receiver R is in the cross member of the Wheatstone bridge, two adjacent arms of which on one side have the respective interposed equal condensers C. The transmitter T is connected to the apex formed by the junction of the conductors for these two condensers C. The remaining two arms of the bridge are formed by the cable 10 and the artificial line now to be described in detail.

For the part of the artificial line lying nearest to the bridge, in an electrical sense, there is employed a series of conductors 11 of the same dimensions and material as the

cable conductors, and loaded in the same way. The cable conductors are surrounded with gutta percha or other suitable insulation, but it is not necessary to simulate this condition in the artificial line. The sections 70 of taped conductor in the artificial line may be of different lengths, shorter near the bridge and longer away from it. However, more conveniently, they may be of the same length, say each 60 feet. These sections will 75 be connected in series through small adjustable inductance coils 12 and resistances 13. Condensers 14 are connected on one side to points adjacent to coils 12 and on the other side to ground 15. These condensers are adjustable and are shunted by adjustable resistances 16. For a trans-Atlantic cable of say 2,000 nauts length, the part of the artificial line constructed of taped conductors 11 in the manner just described may properly aggregate something like 100 nauts in length. Assuming that the sections are each 60 feet long this will require about 10,000 sections. These sections must be disposed and grouped according to well known principles to make 80 the inductive effects negligible between different parts thereof.

There are four fundamental physical constants in the cable which must first be considered for the purpose of matching the artificial line to the cable. These are the resistance, capacity, inductance and leakance. By making the conductor of the sections 11 of the same material and cross-section as the conductor of the cable, the series resistance per unit length is matched to a close first approximation. It is well known that cables are manufactured in sections which are spliced together before laying. The manufacturing methods employed necessarily result in small differences for the constants for these sections. Whatever the constants are for the various sections of the cable, it is assumed that they will be made the same for the corresponding sections of the artificial line 11, so that each naut of its 100 nauts will have the same resistance as the corresponding naut of the cable. Precision of adjustment will be secured by the use of the small interposed adjustable resistances 13. 105

The portion 11 of the artificial line, has not only the same conductor as the cable, but it has the same inductive material wound helically thereon. Therefore, to a close first approximation the series inductance of the artificial line 11 will be the same as of the first 100 nauts of the cable, naut for naut, but the small interposed adjustable inductance coils 12 will facilitate making a precise adjustment to secure equality of inductance between the cable and the artificial line, naut by naut. 110

The distributed shunt capacity for the cable will be sufficiently simulated in the artificial line by the condensers 14, each with 115

one plate grounded and the other plate connected to the cable at a sixty foot interval. Each condenser 14 will have substantially the same electrostatic capacity as a sixty foot 5 length of the actual cable.

The effect of "dielectric hysteresis" of the insulating covering of the cable is equivalent in its reaction on the cable circuit to a high resistance in shunt to a perfect condenser. 10 Accordingly, the high adjustable resistances 16 are provided, shunting the respective condensers 14, and by means of these resistances the effect of the dielectric hysteresis of the cable insulating material can be closely simulated. 15

The attenuation will determine a current in the actual cable that will be somewhat as shown in Fig. 2, where the abscissæ represent distances in nauts from the sending 20 end and the ordinates represent the currents at the corresponding points in the cable. At 100 nauts distance the current will have dropped from its sending value OA to the value indicated by the ordinate DP. Supposing that the whole arriving current at 25 this point were reflected back toward the sending end, the current that would get back to the sending end would be only that corresponding to the ordinate D'P'. But, 30 of course, any reflection irregularity will produce only a small fraction of a total reflection. It will be apparent that for irregularities in the line further out, that is, say, further than 100 nauts along the cable, the 35 effects due to partial reflections will be comparatively small at the sending end. Thus, it becomes apparent that it is the head end of the artificial line for which the most accurate adjustment is required, and that is the 40 reason why the continuously loaded artificial line 11 has been employed for the head end as shown in Fig. 1, instead of an artificial line with lumped loading. After this 45 continuously loaded artificial line has been carried to a suitable length, as at the point 17 in Fig. 1, it is continued in the form of an artificial line made up of lumped elements as will now be explained.

For the part of the artificial line corresponding to the next few hundred nauts of the cable, there are provided sets of elements in succession, each set comprising a series inductance coil 19, a series resistance 18 and a shunt condenser 20. To a first 50 approximation, the inductance coil 19 has an inductance slightly less than a certain definite length of the cable 10; the resistance 18 (with whatever resistance may be in the coil 19) is the same as the resistance of the 55 same length of the cable 10, and the condenser 20 has the same capacity as the capacity of that same length of the cable 10.

Associated with each such group of coils 19 and 18 and condenser 20 there are also 60 a small adjustable air core inductance coil

21 in series and an adjustable high resistance coil 30 in shunt to the condenser 20. The function of the resistance 30 is substantially the same as of the resistance 16. The condenser 20 is more nearly "perfect" than 70 the distributed capacity of the cable, and the resistance 30 in shunt to the condenser 20 makes the functional likeness more nearly exact. The purpose of the adjustable inductance coil 21 will be explained presently. 75

The magnitudes of the successive resistances 18 and coils 19 may be graded, being made smaller at locations closer to the bridge and thus facilitating closer adjustment where the simulation to the actual line 80 needs to be more exact. In this case the condensers 20 will be graded in like manner.

The use of the inductive material on the cable causes it to have an inductance L that is not constant but is dependent on the magnitude of the current. This may be pointed out with reference to Fig. 3. The curve 22 is the ordinary B—H curve for permalloy, with appropriate scales for the co-ordinates. H stands for applied magnetizing force and 85 B stands for the magnetic induction developed in the material. The curve 23 in the same figure is the μ —H curve where $\mu=B/H$. The values of H involved in cable transmission are low and they fall off very 90 rapidly with distance from the transmitting end, so that beyond the first hundred nauts of the cable and in the corresponding part of the artificial line, only a narrow range, say from O to X on Fig. 3 is involved. 100

By the application of suitable constant factors of proportionality, the μ —H curve can also be regarded as an L—I curve, where L is the inductance and I is the current. The problem of simulating the loaded line 105 may be said to involve the problem of making the artificial line have the same L—I curve as the cable. This means that for corresponding points in the two lines, the L—I curve shall be the same for both lines. In ad-

dition the hysteresis loss in the artificial line must be the same at each point as for the corresponding point along the length of the cable, but at points far out on the cable, its effect will be practically negligible, and the 110 criterion of matching the L—I curves will be sufficient. If the inductance were constant the L—I curve would be a horizontal line but its slope expresses the fact that the inductance is a ratio whose value varies 115 dependently upon the variation of the current. If the core material is different from permalloy then it must be worked at a flux density to compensate for the difference and make the L—I curve the same for the 120 permalloy loaded cable and the artificial line. In the present case, in order to make the lumped artificial line as nearly as possible like the cable, the same inductive material is employed, that is, the cores of the 125

130

coils 19 are made of permalloy, heat-treated and otherwise prepared in the same way as the permalloy tape wound on the cable itself. By this feature of construction an important step is taken to make the artificial line closely simulate the actual line.

Not only is permalloy employed for the cores of the inductance coils 19, but in addition these coils and cores are designed so that the permalloy is worked at the same magnetic density as in the cable, that is, if a steady current of a certain number of microampères flowing along the cable produces a certain flux density in the material of the surrounding tape, then the coils 19 are designed so that the same current flowing in their windings will produce the same flux density in their core material. In this way, the assurance is gained that the same curve 23 in Fig. 3 will be followed for corresponding points of the cable and the artificial line.

In the cable certain losses due to eddy currents in the loading material will be inevitable and accordingly the cores of the coils 19 are laminated to such a thickness as to make the alternating current losses here the same as in the cable for the same currents in the respective conductors.

Another feature of construction that is employed in connection with the series inductance coils 19 is to make them with air gaps and to make these air gaps adjustable. The purpose of the adjustable air gaps is to adjust the inductance of the coils. An increase of the air gap will diminish the inductance of the coil, and vice versa. However, the same increase of the air gap that diminishes the inductance will more rapidly diminish the rate of variation of the inductance with current strength. In other words, referring to Fig. 4, an increase of the air gap, will change the L—I curve from 27 to 28, but if the ordinates are multiplied by a constant for curve 28, it cannot be brought to coincide with curve 27 but may be brought to such a locus as curve 29. This is shown by the following considerations.

Let—

M =magnetomotive force impressed in the circuit,

R =reluctance of circuit,

B =flux density at the air gap,

l =length of the iron portion of the circuit,

l_g =length of the air gap,

A =cross-sectional area of the air gap,

H_i =magnetic field intensity in the iron,

$\mu(H_i) = \frac{B}{H_i}$ =permeability of the iron as

a function of magnetic field intensity.

The equations of a magnetic circuit comprising a number of iron elements of various

dimensions and permeabilities, and an air gap, are—

$$M = BA \cdot R \quad (1)$$

and—

$$R = \sum \frac{l_j}{\mu_j A_j} + \frac{l_g}{A} \quad (2)$$

$$\sum l_j = l$$

where l_j , A_j and μ_j are the length, cross-section, and permeability of the j th element. Equation (2) can be written

$$AR = \sum \frac{l_j}{\mu_j A_j} + l_g$$

$$= \frac{l}{\mu} + l_g.$$

where μ may be considered as the mean permeability of the iron. Equation (1) becomes—

$$M = \frac{B}{\mu} l + Bl_g,$$

and can be written in the two forms—

$$H = H_i + H_g, \quad (3)$$

and—

$$\frac{l}{\mu'} = \frac{l}{\mu} + \frac{l}{\mu_g}, \quad (4)$$

where $\mu_g = \frac{l}{l_g}$ may be termed the effective permeability of the air gap, $\mu' = \frac{Bl}{M}$ is the effective permeability, and $H = \frac{M}{l}$ is the mean magnetic field intensity around the circuit or the actual field intensity in the absence of an air gap. From equation (4) μ' can be computed when the value of μ and the dimensions of the air gap are known.

The variation of the effective permeability with impressed field intensity H will now be determined. For small values of H the μ — H curve for iron can be written—

$$\mu(H) = \mu_0(1 + aH + bH^2) \quad (5)$$

therefore—

$$B = \mu(H_i)H_i = \mu_0H_i + a\mu_0H_i^2 + b\mu_0H_i^3 \quad (6)$$

and—

$$H_g = \frac{B}{\mu_g} = \frac{\mu_0H_i}{\mu_g} + \frac{a\mu_0H_i^2}{\mu_g} + \frac{b\mu_0H_i^3}{\mu_g} \quad (7)$$

whence—

$$H = H_i + H_g = \left(1 + \frac{\mu_0}{\mu_g}\right) H_i + \frac{a\mu_0}{\mu_g} H_i^2 + \frac{b\mu_0}{\mu_g} H_i^3. \quad (7)$$

This relation can be inverted by substituting—

$$H_i = \alpha H + \beta H^2 + \gamma H^3$$

In equation (7) and determining α , β , γ in terms of a , b , μ_0 .
This gives—

$$5 \quad H_1 = \frac{\mu'_0}{\mu_0} H - a \frac{\mu'_0}{\mu_0} \left(\frac{\mu'_0}{\mu_0} \right)^2 H^2 + \left[2a^2 \left(\frac{\mu'_0}{\mu_0} \right)^2 - b \frac{\mu'_0}{\mu_0} \right] \left(\frac{\mu'_0}{\mu_0} \right)^3 H^3 \quad (8)$$

10 where—

$$\mu'_0 = \frac{\mu_0 \mu_g}{\mu_0 + \mu_g}$$

is the initial value of μ' as obtained from (4). Substituting (8) in (6) gives B in 15 terms of H —

$$20 \quad B = \mu'_0 H + a \mu'_0 \left(\frac{\mu'_0}{\mu_0} \right)^2 H^3 + \mu'_0 \left[b - 2a^2 \frac{\mu_0 - \mu'_0}{\mu_0} \right] \left(\frac{\mu'_0}{\mu_0} \right)^3 H^5 \quad (9)$$

whence—

$$25 \quad \mu' = \frac{B}{H} = \mu'_0 (1 + a' H + b' H^2) \quad (10)$$

where—

$$a' = a \left(\frac{\mu'_0}{\mu_0} \right)^2$$

$$30 \quad b' = \left(b - 2a^2 \frac{\mu_0 - \mu'_0}{\mu_0} \right) \left(\frac{\mu'_0}{\mu_0} \right)^3 \quad (11)$$

From equations (10) and (11) it is evident that the introduction of an air gap in a 35 magnetic circuit causes a much greater reduction in rate of change of permeability than in the permeability itself. For example, if the air gap is such as to reduce the initial effective permeability of the circuit to one-half its previous value the rate 40 of change of permeability is reduced to one-eighth its former value for small values of H , or the ratio of rate of change of permeability to initial permeability is reduced to one-fourth of its former value.

45 Having provided for adjustment of the air gap of each coil 19, the foregoing considerations show that this introduces an undesirable change in the ratio of rate of change of inductance to current strength. 50 With the end in view to compensate this effect, the small series adjustable air core inductances 21 are employed. By means of an adjustable inductance 21, the inductance can be varied without varying the rate at 55 which the inductance changes with current, so that with the two adjustable coils 19 and 21, a desired adjustment of both of these factors can be secured.

60 Farther out on the artificial line a different method is employed for adjusting the inductance of the coils, as shown for the coils 19'. These may be made with permalloy cores like the others, but they do not have adjustable air gaps and the adjustable 65 air core coils 21 are not employed.

Around each core for the series artificial line windings 19' there is a separate conductive winding 24 and in circuit therewith a battery and an adjustable resistance 25. As shown in Fig. 5, it will be seen that although L varies with I ordinarily as shown by curve 27, yet for a superposed direct current and a narrow range of associated variable current, the apparent value of L varies as shown by curve 26. By adjusting 70 the direct current in the winding by means of the adjustable resistance 25 the core is kept at any desired point on the curve 26 of Fig. 5, and since the ordinates of this curve represent inductance it will be seen 75 that an adjustment of inductance is secured by this means.

Still farther out on the artificial line, where reflection irregularities will be extremely small in their unbalancing effect at 80 the bridge, there is a network of usual construction with fixed inductances, capacities and resistances designated 32 in Fig. 1.

What is claimed is:

1. An artificial line comprising continuously loaded conductor sections in series, and lumped impedance elements between said sections. 90

2. An artificial line comprising continuously loaded conductor sections in series, and lumped impedance elements between said sections and in series therewith. 95

3. An artificial line comprising continuously loaded conductor sections in series, lumped impedance elements between said sections and in series therewith, and shunt lumped impedance elements connected between said sections. 100

4. An artificial line comprising continuously loaded conductor sections in series, and lumped inductance elements between said sections. 105

5. An artificial line comprising conductor sections in series, each with uniform inductance in substantial amount, and small adjustable lumped inductances alternating with said sections in series. 110

6. An artificial line comprising continuously loaded conductor sections in series and small adjustable lumped inductances 115 and resistances between consecutive sections in series.

7. An artificial line comprising continuously loaded conductor sections in series, shunt condensers connected between consecutive sections, and high resistances in parallel with said condensers. 120

8. An artificial line comprising conductor sections continuously loaded with a magnetic alloy consisting chiefly of nickel and iron, adjustable lumped inductance elements between said sections and in series therewith, and lumped shunt capacity elements between said sections. 125

9. In combination, a submarine cable con- 130

- tinuously loaded with a magnetic alloy consisting chiefly of nickel and iron, and an artificial line for balancing said cable comprising two sections of conductor of the same kind as the main cable core and loaded with said alloy in the same manner, an adjustable lumped inductance between said sections, a shunt condenser between said sections, a plurality of lumped inductance coils 5 in said artificial line more remote from the connection to said cable than said continuously loaded sections, and a core composed of said alloy for each of said coils.
10. In combination, a smooth signaling conductor, transmitting and receiving apparatus associated with one end thereof and a balancing artificial line connected with that end, the part of said line nearest said end comprising series connected sections of 15 smooth conductor like said signaling conductor in respect to the series impedance characteristics thereof and lumped shunt impedance devices connected in alternation with said sections corresponding in value 20 with the shunt impedance characteristics of the portions of the signaling conductor of the same lengths as the corresponding sections.
11. In combination, a smooth signaling conductor, transmitting and receiving apparatus associated with one end thereof and a balancing artificial line connected with that end, the part of said line nearest said end comprising series connected sections of 25 smooth conductor approximately like said signaling conductor and small adjustable lumped elements in series between the sections to facilitate exact adjustment.
12. In combination, a smooth signaling conductor, transmitting and receiving apparatus associated with one end thereof, and a balancing artificial line connected with that end, the part of said line nearest said end comprising series connected sections of 30 smooth conductor like said signaling conductor, condensers connected in shunt between the sections and having substantially the same capacity as lengths of the signaling conductor corresponding to said sections, and adjustable resistances in parallel 35 with said condensers to make the total shunt path at each point between sections of the same value and character as the distributed shunt path for the corresponding part of 40 the signaling conductor.
13. In combination in an artificial line, sections of continuously loaded conductor, small adjustable inductances and resistances interposed in series between such sections 45 and adjustable condensers and resistances connected in shunt between said sections.
14. In combination, a signaling conductor loaded continuously by means of a certain permeable material, transmitting and receiving apparatus associated with one end 50 thereof and a balancing artificial line connected with that end, the part of said line nearest said end comprising a smooth conductor loaded with the same permeable material in the same manner as for said signaling conductor and said line farther out comprising coils with the same material for their cores.
15. In an artificial line to simulate a continuously loaded line, inductance coils having adjustable air gaps. 75
16. In an artificial line to simulate a continuously loaded line, inductance coils having adjustable air gaps and in series alternation therewith adjustable air core inductance coils. 80
17. In an artificial line to simulate a continuously loaded signaling conductor, two kinds of adjustable inductance coils in series alternation, one with a core of permeable material and an adjustable air gap, the other with an air core and adjustable as to its inductance, whereby, with relative adjustment, the signaling conductor can be simulated. 85
18. In combination, a signaling conductor continuously loaded with a certain permeable composition, transmitting and receiving apparatus associated with one end thereof and a balancing artificial line connected with that end and comprising coils with cores of the same said material and with adjustable air gaps, the dimensions of said coils and cores being such that the material is worked at the same magnetic flux 90 density as on the signaling conductor. 95
19. In combination, a continuously loaded signaling conductor, transmitting and receiving apparatus associated with one end thereof and a balancing artificial line connected with that end, said artificial line comprising inductance coils with cores, said coils and cores being proportioned to give the same inductance current characteristic in the artificial line as in the signaling conductor. 100
20. In combination, a continuously loaded signaling conductor, transmitting and receiving apparatus associated with one end thereof and a balancing artificial line connected with that end, said line comprising coils and cores with adjustable air gaps for which the adjustment varies the inductance less than the rate of change of inductance with current, and adjustable air core coils 105 in series by which compensation may be effected to make the artificial line simulate the loaded conductor. 115
21. In combination, a signaling conductor continuously loaded with a magnetic alloy 110 consisting chiefly of nickel and iron, transmitting and receiving apparatus associated with one end thereof and a balancing artificial line connected with that end, the part of said line nearest said end comprising a 115
- 120
- 125
- 130

smooth conductor continuously loaded with said alloy like the signaling conductor and the said line farther out comprising coils having cores composed of said alloy.

5 22. In combination, a continuously loaded signaling conductor, transmitting and receiving apparatus associated with one end thereof and a balancing artificial line connected with that end, said line comprising 10 series elements and shunt condensers at intervals, each said condenser having an adjustable high resistance in parallel therewith.

15 23. In an artificial line to simulate a continuously loaded signaling conductor, inductance coils in series and resistances connected in series alternately with said coils, the values of said resistances being enough when taken with the resistances of the inductance coils to simulate the line with respect to both inductance and resistance.

20 24. In combination, a continuously loaded signaling conductor, transmitting and receiving apparatus associated with one end thereof and a balancing artificial line connected with that end, said line comprising inductance coils with cores of permeable material, auxiliary coils on said cores and adjustable direct current sources to energize 30 said last mentioned coils.

25 25. In an artificial line to simulate a continuously loaded signaling conductor, inductance coils with cores of the same material as the continuous loading material for the signaling conductor, said cores also having thereon auxiliary coils and adjustable direct current sources to energize said auxiliary coils.

30 26. The combination with a continuously loaded signaling conductor, of an artificial line simulating said conductor including inductance coils with cores of the same material as the loading material, said coils and cores being designed to have an L—I curve 45 for each point of the artificial line simulating that of the signaling conductor for the corresponding point.

27. The combination with a continuously loaded signaling conductor, of an artificial line simulating said conductor including inductance coils with cores of the same material as the loading material, said coils and cores being designed to have an L—I curve for each point of the artificial line simulating that of the corresponding point 50 of the signaling conductor and also simulating the hysteresis loss of the loaded signaling conductor.

28. The method of producing a balancing impedance in an artificial line equal to the impedance of a signaling conductor continuously loaded with magnetic material, which consists in working the magnetic material at each point of the artificial line on approximately the same L—I curve as for the corresponding point of the signaling conductor. 60

29. The method of producing a balancing impedance in an artificial line equal to the impedance of a signaling conductor continuously loaded with magnetic alloy, which consists in working the magnetic material at each point of the artificial line on approximately the same L—I curve as has the corresponding point of the signaling conductor 70 and at the same hysteresis loss. 75

30. The method of adjusting the inductance of the coils in an artificial line to balance a continuously loaded signaling conductor, which consists in introducing a variable amount of substantially constant permeability substance in the magnetic circuits of at least a portion of said coils. 80

31. The method of adjusting the inductance of coils in an artificial line to balance a continuously loaded signaling conductor, 85 which consists in superposing the field of a local direct current on the cores of said coils and adjusting the magnitude of said direct current.

In witness whereof, I hereunto subscribe my name this 2nd day of August A. D., 1922.

OLIVER E. BUCKLEY.
